UNITED STATES PATENT OFFICE.

JOHN N. HELTZEL, OF WARREN, OHIO.

CONCRETE FORM.

Application filed November 4, 1925. Serial No. 66,806.

The present invention relates to concrete forms, and aims to provide improvements in forms used for molding curbs, curbs and gutters, walls, sidewalks, and the like, this 5 application being in part a continuation of my copending application Serial No. 17,211 filed March 21, 1925 and disclosing improvements as over the concrete forms disclosed in said copending application.

10 Another object of the invention is the provision of a concrete form including a division plate which may be inserted and withdrawn transversely in a convenient and efficient manner.

15 A further object is the provision of novel means for connecting spaced form rails or side members to hold them in spaced relation, as well as maintaining the side rails or members at each side in alinement and joined 20 together, and which means is adapted to accommodate a division plate for movement into and out of the form transversely of the form without disturbing the side rails or members and other parts of the form which 25 may remain in original position.

30 A still further object is the provision of means for simultaneously, or with a single device, spacing the form rails or side members apart and joining the adjacent ends thereof, as well as accommodating a division 35 plate in a convenient, practical and simple manner.

Still another object is the provision in a 40 form of the kind indicated of means for removably holding a face rail or similar form member which may be detached transversely without separating other rails or form members of the form.

With the foregoing and other objects in 45 view, which will be apparent as the description proceeds, the invention resides in the construction and arrangement of parts, as hereinafter described and claimed, it being understood that changes can be made within 50 the scope of what is claimed, without departing from the spirit of the invention.

The invention is illustrated in the accompanying drawings, wherein—

Figure 1 is a perspective view of a concrete 55 curb form embodying the improvements.

Fig. 2 is a side elevation of a portion of the form showing one of the joints.

Fig. 3 is a horizontal section on the line 3—3 of Fig. 2.

Fig. 4 is a perspective view of a modified construction or a special form.

Fig. 5 is a side elevation of the form shown in Fig. 4, showing one of the joints of the form.

Fig. 6 is a cross section on the line 6—6 60 of Fig. 5.

The concrete form shown in Figs. 1, 2 and 65 3 is intended especially for producing street or road curbs, although the same or similar forms may be used for molding walls, sidewalks, and similar structures, it being understood that the side rails or form members 14 of the form may be of different heights and may be spaced apart different distances according to the work to be done. Said rails 70 or side members 14 are composed of sheet metal and have the webs 15, forming the side walls of the mold, and said rails have the outturned tread and base flanges 16 and 17, respectively, at the upper and lower edges of 75 the webs. The tread flanges 16 have the secondary downturned flanges 18, and the base flanges 17 have the secondary upturned flanges 19.

In order to connect the opposite rails or 80 side members and space them apart the desired distance, as well as to join the alining rails end to end, connecting and joint yokes or arches 20 are provided. Each yoke comprises pairs of spaced bars 21 constituting 85 the limbs of the yoke, and an upper cross bar 22 welded or otherwise secured between the upper terminals of the bars 21. The cross bar 22 serves as a spacer between the upper ends of the bars 21 to space the bars 21 apart, 90 so that the limbs of the yoke have the slots 21' and spacers 22' are also welded or otherwise secured between the lower terminals of the bars 21. The limbs of the yoke may be either vertical or inclined, according to the 95 type of curb that is to be produced. As shown, one limb of the yoke is vertical and the other limb is inclined to produce a "battered" curb, but both limbs may be vertical when a "straight" curb is to be produced. Pins or dowels 23 are welded or otherwise secured to the opposite sides of the bars 21, and do not extend through the slots 21', and said dowels project from opposite 100 sides of the limbs of the yoke.

The yokes 20 are disposed between the adjacent ends of the rails, and the rails are provided with means at their ends to engage the yokes so as to space the rails apart and aline them. Thus, the rails have outturned 105 end flanges 24. These flanges 24 extend upwardly and downwardly between the base 110

and tread flanges and are preferably flush with the ends of the rails. Said flanges 24 are conveniently provided by welding or otherwise securing angle irons 25 to the webs 15 at the outer sides of the rail. The flanges 24 are provided with apertures 26 to receive the dowels 23, in order that the yoke and rails may be moved together into engagement longitudinally of the form. It will be apparent that the yoke may be readily moved longitudinally of the form into engagement with the flanges 24 of a pair of rails, after which the next adjoining rails may be moved longitudinally into engagement with the yoke. The dowels 23 will align the rails at the opposite sides, and maintain them in accurate alignment, and the yoke will also space the opposite rails apart the desired distance, according to the length of the cross bar 22. The yoke 20 thus serves as a spacer or cross connection between the side rails or forms, as well as providing a joint member to connect the rails end to end.

Each yoke 20 is also adapted to accommodate a division plate 27 which may be inserted transversely through the slots 21 of the limbs of the yoke. The division plate 27 is of a width to extend across the space between the opposite side rails or form members, so as to divide the curb or other concrete structure, and the division plate may also be used as an end wall for the mold. A suitable handle 28 is welded or otherwise secured to the division plate at one vertical side edge thereof for conveniently inserting and withdrawing the plate.

The division plates are readily inserted in the yokes after the form is set up, and it will be noted that the cross bars 22 of the yokes are spaced above the tread flanges of the rails 14 in order that a trowel or other finishing tool may be moved over the concrete under the bars 22 in finishing off the top surface of the concrete. After the concrete has started to set, the division plates 27 may be withdrawn, and in pulling the division plates out of the form transversely or through either side of the form, this will avoid disturbing or tearing up the concrete at the surface thereof. After the concrete has set the rails and yokes may be removed by pulling them apart longitudinally of the form.

The form shown in Figs. 4, 5 and 6 comprises the relatively high back or outer rails 14^a, and the relatively low front or inner rails 14^b on which are disposed the face rails 14^c. The rails 14^a and 14^c are of the same cross-section as the rails 14 hereinbefore described, but the rail 14^b is of special cross-section, having the inwardly extending tread flange 16^b on which the rail 14^c is seated, and having the outwardly extending base flange 17^b. The yoke 20^a comprises the spaced side bars 21^a forming one limb, the spaced side

bars 21^b forming the other limb, and the cross bar 22^a secured between the upper terminals of said side bars, spacers 22^b being secured between the lower ends of the side bars. The bars 21^a have the dowels 23^a to extend through the apertures of the end flanges 24^a of the rails 14^a similar to the construction shown in Figs. 1, 2 and 3. The bars 21^b have dowels 23^b extending through apertures in end flanges 24^b with which the rails 14^b are provided at their outer sides above the flanges 17^b. Said bars 21^b also have dowels 23^c to extend through apertures in end flanges 24^c at the inner sides of the rails 14^b below the flanges 16^b. The dowels 23^b and 23^c are thus located at the outer and inner sides of the webs of the rails 14^b, but the joint between the rails 14^b is substantially the same as the joint between the rails 14^a.

The division plate 27^a is inserted through the slots of the limbs of the yoke 20^a, and has openings 28^a adjacent to its vertical side edges to provide handles for conveniently inserting and withdrawing the division plate at either side of the form.

The face rail 14^c is removably held by the yokes 20^a and rails 14^b. Thus, apertured ears or lugs 40 are secured to the opposite sides of the bars 21^b of each yoke, and the rails 14^c are seated on the flanges 16^b of the rails 14^b below the ears 40 with the ends of the rails 14^c abutting the yokes. The flanges 16^c and 17^c of the rails 14^c and the flanges 16^b have apertures 41 alining with the apertures of the ears 40, and rods 42 are inserted downwardly through the ears 40 and apertures 41, thereby holding the rails 14^c in place during the pouring of the concrete. Then, after the concrete has set sufficiently, the rods 42 may be withdrawn and the rails 14^c removed inwardly or transversely, thereby exposing the face or inner side of the curb so that same may be finished off by trowels or other suitable finishing tools, the rails 14^a and 14^b and yokes 20^a remaining assembled after the rails 14^c are removed.

Having thus described the invention, what is claimed as new is:

1. A joint member to be disposed between other members of a concrete form, and a division plate slidable through said joint member to be projected into and withdrawn from the form.
2. A joint member for a concrete form having a slot for the passage of a division plate therethrough.
3. A joint member for a concrete form having a slot for the insertion of a division plate and having dowels at opposite sides of said slot for the engagement of other form members.
4. A yoke for use in a concrete form, and a division plate slidable through one limb of said yoke.

5. A yoke for use in a concrete form having one limb provided with a slot for the insertion of a division plate.
6. A yoke for use in a concrete form, and a division plate slidable in the limbs of the yoke, said limbs having dowels at opposite sides for the engagement of other form members.
7. A yoke for use in a concrete form whose limbs are provided with slots for the insertion of a division plate and dowels at the opposite sides of the limbs for the engagement of other form members.
8. A concrete form comprising rails disposed end to end, a joint member between the ends of said rails, and a division plate slidable horizontally through said joint member between the ends of the rails.
9. A concrete form comprising rails disposed end to end, and a joint member disposed between the ends of said rails and having a slot for the passage of a division plate.
10. A concrete form comprising opposite side rails disposed end to end, a yoke having limbs disposed between the ends of the rails at opposite sides, and a division plate slidably horizontally in the limbs of said yoke.
11. A concrete form comprising opposite side rails disposed end to end, and a yoke having limbs disposed between the ends of the rails at the opposite sides, said limbs having slots for the insertion of a division plate.
12. A concrete form comprising rails disposed end to end, a joint member having spaced bars, said bars and rails having interengaging portions, and a division plate slidable horizontally between said bars.
13. A concrete form comprising opposite side rails disposed end to end, a yoke having limbs disposed between the ends of the rails at the opposite sides, each limb being composed of spaced bars, said bars and rails having interengaging portions, and a division plate movable horizontally between said bars.
14. A concrete form comprising rails disposed end to end, joint members between the ends of said rails, said rails and members having interengaging portions, other rails disposed between said members and removable transversely from between them, and means for holding the lastnamed rails in place.
15. A concrete form comprising rails disposed end to end, joint members between the ends of said rails, said rails and members having interengaging portions, other rails disposed between said members and removable transversely from between them, and rods insertable through the lastnamed rails, said members having portions for the engagement of said rods.
16. A concrete form comprising opposite side rails disposed end to end, and including lower and upper rails at one side, yokes having their limbs disposed between the ends of the rails at the opposite sides, said lower rails and the opposite side rails and yoke having portions fitted together longitudinally of the rails, said upper rails being removable transversely from between the yokes, and means for holding said upper rails in place.
17. A concrete form comprising opposite side rails disposed end to end, and including lower and upper rails at one side, yokes having their limbs disposed between the ends of the rails at the opposite sides, said lower rails and the opposite side rails and yoke having portions fitted together longitudinally of the rails, said upper rails being removable transversely from between the yokes, and rods insertable through the end portions of said upper rails and into said lower rails, the yokes having apertured portions to receive said rods.
18. A concrete form comprising rails disposed end to end, a joint device between the ends thereof, and rods connecting said rails and device.
19. A concrete form comprising rails disposed end to end and having upper and lower flanges, a joint device between the ends of the rails, and rods connected with said device and extending through said flanges to hold the rails in abutment with said device.
20. A concrete form comprising rails disposed end to end and having upper and lower flanges, a joint device between the ends of the rails, and rods extending through said flanges, said device having portions engaging said rods.
21. In a concrete form, a joint member to be disposed between the ends of rails, and rail engaging rods, said device having portions to receive said rods.
22. In a concrete form, a joint device to be disposed between the ends of rails and having projecting portions, and rods engageable through said portions and adapted to engage the rails.
23. A concrete form comprising rails disposed end to end, a joint device at the adjacent ends of the rails, and rods extending through said rails, said device having portions to receive said rods.
24. A concrete form comprising rails disposed end to end, a yoke member having portions projecting therefrom, and rods engaging through said portions and rails for connecting the rails and yoke member together.
25. A concrete form comprising opposite side members disposed end to end, a yoke at the adjacent end portions of said members, and means for securing said members to said yoke to prevent longitudinal separation thereof.

26. A concrete form comprising side members disposed end to end, a joint device at the adjacent ends thereof, and means for securing said members and device together and adapted to release said members for lateral movement away from said device.
27. A concrete form comprising side members, a joint device at the adjacent ends thereof, and removable securing means for holding said members and device together against separation, said members being re-

movable transversely when said securing means are removed.

28. A concrete form comprising side members, a joint device between the ends thereof, and means for securing said members and device together in abutment and adapted to release said members for transverse removal.

In testimony whereof I hereunto affix my signature.

JOHN N. HELTZEL.
